SANDING DEVICE FOR VEHICLES

John B. Lintern, Berea, Ohio, assignor to The Lintern Corporation, Cleveland, Ohio, a corporation of Ohio

Application July 22, 1937, Serial No. 155,057

4 Claims. (Cl. 291—44)

This invention relates to sanding devices for vehicles such as are more fully described in my copending application for Letters Patent, Serial No. 140,002, filed April 30, 1937, and particularly to a new and improved combined discharge header and conduit for use in connection therewith.

The principal object of the present invention is to provide a combined discharge header and distributing conduit which may be readily connected to a sand hopper and which provides a water-tight joint between the discharge point of the sand and the header.

Another object is to provide a flexible discharge header and distribution conduit combination so arranged that striking of the conduit or any part of the combination by obstructions during movement of the vehicle cannot damage the header and conduit or the remainder of the sanding apparatus.

20 A still further object is to provide a discharge conduit which vibrates under the impact of the relatively rearwardly moving air stream occasioned by the forward motion of the vehicle and thus assists in maintaining the device free from possible clogging and the like.

Other objects and advantages will become apparent from the following specification, wherein reference is made to the drawing, in which:

Fig. 1 is a side elevation of an automobile with the sanding device installed on the running board;

Fig. 2 is an enlarged fragmentary vertical section of the running board and sand hopper and the combined discharge header and distribution conduit of the present invention connected thereto; and

Fig. 3 is an enlarged sectional view taken on a plane indicated by the line 3—3 in Fig. 2.

As more fully described in my copending application, the sander comprises a cylindrical hopper 1 in which is disposed a solenoid operating coil enclosed in a suitable protecting casing 2, the solenoid coil directly operating the stem of a control valve 3. The valve 3, in turn, cooperates with a downwardly constricted central throat 4 on the bottom of the hopper 1 for controlling the discharge of sand from the hopper 1. The hopper is cylindrical in form and is preferably disposed on the running board 5 of an automobile 6, a suitable clamping collar 7 being provided for engaging with the lower end of the hopper 1 for securing it in position. As described in my copending application, it is desirable that the discharge end of the distribution conduit which receives the sand discharged from the throat 4

be offset from the axis of the throat so that upon rotation of the hopper about its upright axis, the discharge end of the conduit will be adjusted laterally of the vehicle wheel with which it is associated. In the prior application, above referred to, there was provided on the underside of the hopper and throat 4 a cast metal header to which the upper end of the distribution conduit was connected. Such metal header necessarily extended a considerable distance below the running board and consequently was apt to be struck against an obstruction during travel of the car and thereby become damaged or damage the remainder of the apparatus. Furthermore, some difficulty was encountered in properly and economically sealing the joints between the metal header and the underside of the hopper and between the header and the discharge conduits.

Instead of the metal header and attached distribution conduits, the distribution conduit herein disclosed is provided. This conduit comprises an imperforate resilient rubber tube 10 having at its lower end an integral enlarged shield 11, the walls of the shield being of less thickness than the walls of the tube 10 so that any obstruction striking the shield may be relieved by flexing of the shield without appreciably disturbing the tube 10. The lower end of the tube 10 is open, as indicated at 12, the opening being somewhat restricted and being spaced radially inwardly 30 from the side wall of the shield by a peripheral downwardly and inwardly sloping shoulder 13, so that sand dropping therefrom does not touch the side walls of the shield 11. An integral internal annular flange 14 is provided within the shield in spaced relation from the ends thereof to prevent the passage of water by capillary action upwardly along the inner side wall surfaces of the shield. Above the shield 11, the tube 10 is curved through a portion of its length, as indicated at 15, and at its upper end is enlarged to provide an integral header portion 16. An integral external flange 17 is provided about the upper open end of the header portion 16. The header portion 16 is of sufficient size to accommodate the valve and the throat 4 with its discharge end spaced radially inwardly from the header walls so that the throat discharges directly into the tube 10. Thus there are no possible joints or openings for moisture between the lower end of the shield 11 and the throat 4.

The combined distribution conduit and header is secured to the underside of a flange 18 on the throat 4, bolts 19 being provided and extending entirely through the flange 17, the flange 55

18 and the bottom wall of the hopper, and thence engaging a suitable anchor plate 20 within the hopper. A washer 21 underlies the flange 17 and the bolts 19 extend through apertures there-
5 in so that uniform clamping pressure is ex-
erted by the bolts against the underside of the flange 17. Thus by means of the bolts 19, the flange 17 may be drawn tightly against the un-
derside of the throat flange 18, and the flange 18,
10 in turn, drawn tightly against the bottom of of the hopper, the flange 17 yielding and forming a water-tight seal at its point of union with the flange 18.

Due to the resiliency of the tube 10, any ob-
15 struction that might strike it above the level of the shield 11 merely flexes the tube without damaging in any way the remainder of the struc-
ture. The shield 11 is preferably of such thick-
ness that the high speed of relatively rearwardly
20 moving air occasioned by forward movement of the vehicle causes the shield to vibrate and elas-
tically distort even while the force of the air is insufficient to vibrate the tube 10 appreciably and cause too great a displacement of the open-
25 ing 12 relative to the wheel of the vehicle. This action breaks loose any material tending to clog the interior of the shield even while it is dis-
charging the sand in proper relation to the wheel. Likewise, there is a tendency to vibra-
30 tion of the conduit 10 so that any material tem-
porarily accidentally jammed therein is loosened and freed. Since the discharge opening 12 and the discharge opening of the throat 4 are offset with respect to each other, rotation of the hop-
35 per about its upright axis will provide lateral adjustment of the opening 12 with respect to the wheels of the vehicle.

To provide further protection against rain and snow, the bottom of the hopper 1 is spaced slightly above the lower end of the hopper so that the bottom edge of the side wall seats tightly against the rubber mat 24 of the running board.

Having thus described my invention, I claim:

1. A ~~combined~~ discharge header and distribution conduit for a vehicle sander comprising a rubber tube having its upper portion adapted for connection to a sanding device and having a portion depending from said header portion and being open at its lower end, and said tube having an integral rubber shield depending from its lower end, the shield having a wall thickness less than the wall thickness of the tube and capable of elastic deformation by air pressure occasioned by forward motion of the associated vehicle, said shield being substantially coaxial with the lower open end of the tube and having its side wall spaced outwardly from the opening in the tube.

2. A combined discharge header and distribution conduit for a sander for a vehicle and

comprising a rubber tube having its upper por-
tion in the form of a header of enlarged cross section open at its upper end and terminating at its upper end in an integral external flange for connection to a sanding device and having a portion beneath said header portion and with its axis angularly disposed thereto and curving downwardly and being open at its lower end, the lower end having its axis substantially upright and offset from the axis of the header, and the open lower end being restricted internally, and said tube having an integral rubber shield de-
pending from its lower end, the shield having a wall thickness less than the wall thickness of the tube and capable of elastic deformation by air pressure occasioned by forward motion of the associated vehicle, said shield being substan-
tially coaxial with the open end of the tube and having its side wall spaced outwardly from the opening in the tube, and the lower end of the tube protruding partially into the shield.

3. A combined discharge header and distribu-
tion conduit for a vehicle sander comprising a rubber tube having its upper portion in the form of a header of enlarged cross section open at its upper end and terminating at its upper end in an integral external flange for connection to a sanding device and having a portion beneath said header portion and with its axis curving out-
wardly and downwardly from the axis of the header, and being open at its lower end, the lower end having its axis substantially upright and offset from the axis of the header, and the open lower end being restricted internally, and said tube having a portion in the form of an integral rubber readily flexible, thin-walled shield depending from its lower end, said shield being substantially coaxial with the open end of the tube and having its side wall spaced out-
wardly from the opening in the tube, and the lower end of the tube protruding partially into the shield.

4. A sand discharge device for motor vehicle sanders comprising a tube adapted for connec-
tion with a supply for sand, said tube having its lower end approximately vertically disposed in mounted position on such vehicle, and an elongated tubular rubber shield supported on the end of the tube coaxial with the discharge opening of the tube and having all surface portions of its interior which are exposed to sand dis-
charged from the tube spaced radially from the axis of the tube farther than the discharge sur-
face portions of the tube from said axis, and being sufficiently flexible so as to be capable of elastic deformation by air pressure occasioned by forward movement of the vehicle at driv-
ing speed.
